UNITED STATES PATENT OFFICE.

CHARLES J. HARTLEY, OF DECATUR, ILLINOIS.

DESIGN FOR A PUZZLE-BOX.

SPECIFICATION forming part of Design No. 26,662, dated February 16, 1897.

Application filed January 4, 1897. Serial No. 617,962. Term of patent 31 years.

To all whom it may concern:

Be it known that I, CHARLES J. HARTLEY, of Decatur, in the county of Macon and State of Illinois, have invented a certain new Design for a Puzzle-Box, of which the following is a specification.

This design is for a box that is designed to hold blocks the shifting of which into a predetermined correlation constitutes a puzzle; and it consists in the peculiar shape of the box and its parts.

The design is illustrated in isometrical perspective in the drawing forming part of this specification, and the different parts have peculiarities as follows:

The box 1 is rectangular, comparatively shallow, and topless. The lower portion of its internal area is without partitions or other obstructions, and the upper portion of its internal area is separated into three spaces by two strips that are narrower than the internal height of the box. The partition-strip that is designated by 2 is straight, and it extends parallel with a side of the box. The partition-strip that is designated by 3, 4, and 5 has a rectangular jog at 4 that extends at right angles with strip 2, and the portions 3 and 5 extend parallel with said strip. The internal

area of the box is separated into four divisions, one of which is the entire lower portion of the area, another of which is a plain rectangle, bounded on one side by the straight partition-strip, and the others of which are irregular rectangular figures, separated by the jogged partition-strip and consisting, theoretically at least, each of a comparatively large rectangle communicating with a smaller one. In this particular instance the plain rectangle contains ten twenty-fifths of the internal area of the upper portion of the box. The irregular figure next adjoining the rectangle contains seven twenty-fifths of such area, and the other irregular figure contains eight twenty-fifths, but this proportion may be varied somewhat without losing the obvious characteristics of the design.

What I claim as new, and desire to secure by Letters Patent, is—

The design for a puzzle-box herein shown and described.

In testimony whereof I sign my name in the presence of two subscribing witnesses.

CHARLES J. HARTLEY.
